UNITED STATES PATENT OFFICE.

FRANK ROBBINS SMITH, OF TORONTO, ONTARIO, CANADA.

MACHINE FOR SORTING FRUIT.

1,118,957.

Specification of Letters Patent.

Patented Dec. 1, 1914.

Application filed February 2, 1914. Serial No. 816,062.

To all whom it may concern:

Be it known that I, FRANK ROBBINS SMITH, a citizen of the United States, residing in the city of Toronto, county of York, Province of Ontario, Canada, have invented certain new and useful Improvements in Machines for Sorting Fruit, of which the following is a specification.

My invention relates to improvements in machines for sorting fruit, and relates more particularly to the provision of a machine to be used in separating cherries that may pass through the machine patented to me October 28, 1913 under Number 1076794, for machines for stemming cherries, without having the stems removed therefrom, from the cherries the stems of which have been removed by this machine.

The principal object of my invention is the production of a machine to perform the function specified which will be positive in its operation without crushing the fruit.

Another object of my invention is to construct my machine of the fewest possible parts so as to permit repairs to be easily effected.

A still further object of my invention is to construct the feeding cylinder in such a manner that each cherry will readily pass into its individual pocket as the cylinder revolves.

Further objects of my invention will be pointed out in this specification.

Figure 1 is a vertical cross section through my machine illustrating the preferred form of construction thereof. Fig. 2 is a perspective view of portion of the feeding cylinder. Fig. 3 is a perspective view of portion of the sorter. Fig. 4 is a perspective view of the guiding chutes whereby the cherries dropping from the feeding cylinder are directed in their course to the sorter. Fig. 5 is a side elevation partly in section of portion of certain operating gear for the sorter, part of the machine frame being shown in section. Fig. 6 is a plan view of the gearing for operating the sorter, showing one end of the sorter, and also showing the machine frame in section. Figs. 7 and 8 are end elevations of the mechanisms whereby the sorter is locked in normal position at certain times, and Fig. 9 is an end elevation of the gearing for operating the sorter.

In the drawings like characters of reference indicate corresponding parts in each figure.

A is any suitable machine frame in which the operating parts hereinafter mentioned are suitably journaled. B is the feeding cylinder which is suitably journaled in the 60 said machine frame as by means of its shaft C. The cylinder B is longitudinally provided, in opposite sides, with a plurality of longitudinally aligned pockets D, each of which is designed to receive a cherry. By 65 any suitable means such as a drive pulley (not shown), the cylinder B is rotated (as indicated by arrow in Fig. 1) at the desired speed. As each set of pockets D passes by the mouth of the hopper E (which of course 70 is filled with cherries), a cherry is passed by gravity into each of the said pockets, and the said cherries are prevented from prematurely falling thereout by the shield F which is positioned as illustrated in Fig. 1 75 and spaced a short distance away from said cylinder. Any suitable means such as a screw G is used to secure each end of the said shield in place to the machine frame. Positioned underneath the cylinder B is a 80 frame H, comprising a front plate I which carries a plurality of partitions J spaced apart substantially the same distance as that separating the pockets D. The said partitions form guiding chutes K, and these 85 chutes are provided with a floor which is composed of a back plate L positioned as illustrated in Fig. 1. Any suitable means, such as the lugs M carried by the machine frame, and the screw N, are used to secure 90 these said plates in position. Journaled by its shaft 2 in the machine frame, and below the frame H, is a sorter 3. This sorter is provided at each side with a plurality of transverse grooves 4 which are parallel. The 95 said grooves are spaced apart by means of the ribs 5. The space separating the said ribs is substantially the same as that separating the partitions J; in other words, the said ribs are in alinement with the partitions J. The sorter 3 normally occupies substantially the position illustrated in Fig. 1 so that the floor 6 of each groove 4 will have a downward-backward inclined position. When the series of pockets D at the under- 100 side of the cylinder B escape by the lower edge 7 of the shield F, each pocket D (the walls 8 separating the said pockets D are in alinement with the partitions K), discharges 105 its cherry into its corresponding chute K. These cherries fall upon the back plate L 110 which slopes in a downward backward di-

rection. Since the front plate I does not extend down to the lower ends of the partitions J, an opening 9 is formed at the lower end of each chute K, and through 5 these openings the cherries escape each into its allotted groove 4 on the sorter. The cherries without stems run down the inclined floors 6 and are collected in any suitable receptacle 10. The cherries with stems 10 cannot roll over because of the stems attached thereto, and they occupy substantially the positions on the sorter illustrated in Fig. 1, where two cherries are illustrated, one with a long stem and the other with a 15 short stem. In due course, the sorter 3 is turned one-half a revolution in the direction indicated by arrow, discharging the unstemmed cherries into the receptacle 11.

I shall now describe the preferred train 20 of gearing for operating the sorter. Journaled on the stub shaft 12 which is held in the frame A, is a sleeve 13. Keyed to this sleeve is a pinion 14 which is driven by the gear wheel 15 keyed to the shaft C of the cylinder B. Also keyed to the sleeve 13 is a toothed sector 16 which at times is in mesh with the pinion 17 keyed to the shaft 2 of the sorter 3. Immediately the sorter 3 is to be turned one-half a revolution, the teeth 18 25 of the sector 16 come into mesh with the teeth of the pinion 17 and turn this pinion so as to turn said sorter one-half revolution. In order to lock the said sorter in normal position illustrated in Fig. 1, I use the following 30 preferred means: Keyed to the sleeve 13 is a sector 19 with which co-acts the sector 20 keyed to the shaft 2. The speed of rotation of the various members of the gearing described is such that the shaft 2 of the sorter 3 is being revolved while the chord 21 of the sector 19 is opposite the sector 20. Immediately this sector 20 has made a complete revolution, the corner 22 of the sector 19 is positioned a short distance below the 35 corner 23 of the sector 20, at which time the toothed segment 16 is out of mesh with the pinion 17. Cut in the edge of the sector 20, is a depression in the form of an inverted 40 arc 24. The radius of this arc is struck 45 from the center of the stub shaft 12, so consequently as the sector 19 is constantly revolving, the said sector will pass by the 50 sector 20 without conflicting.

From the foregoing description taken in 55 conjunction with Figs. 7 and 8, it will be understood that the contact of the sector 20 with the sector 19 at the inverted arc 24 will effectually prevent the rotation of the sorter 3. Of course in due course said pinion 17 will be operated to invert the sorter 60 3 for the purpose set forth.

a is a chute or shaker over which the cherries pass from the stemming machine already referred to, into the hopper E.

b is a rotary brush journaled by its shaft

c in the head *d* of the machine frame A. Secured to said head D is a vertically disposed plate *e*, positioned above the cylinder B and between the hopper E and the brush *b*. The lower edge of the plate *e* is positioned 70 a short distance above the cylinder B, and this plate is used to prevent the mass of cherries in the hopper becoming entangled with the brush *b*. The said brush *b* prevents broken stems and bits of fruit from 75 passing around with the cylinder, and also brushes any stems carried by the cherries so that they will lie in the most convenient position for their passage by the shield F. Of course any suitable means may be employed 80 to perform the functions of the plate *e* and brush *b*. A portion of the cylinder B, in advance of the pockets D is planed away as indicated clearly in Figs. 1 and 2, to form a ledge or shelf *f* which extends between the outer sides of the pockets at each 85 end of the cylinder in a continuous and unbroken form. The dotted position of one of the pockets D in Fig. 1 shows that the ledge or shelf *f* always passes by the mouth 90 of the hopper E in advance of the pockets D. The construction of this ledge or shelf *f* removes entirely the greater portion of one side of each of the pockets D, thereby 95 facilitating the passage of the cherries into said pockets. It will be understood that the removal of the greater portion of one side of the pockets D will permit the cherries to ride along the shelf or ledge *f* so that they will positively pass into the pockets D. 100 Were the pockets provided with sides all of an equal height, I have found from practice that many of the pockets D would pass by the hopper E without receiving a cherry. Therefore it will be understood that the 105 construction described, or its equivalent, of the said cylinder B is most important. As the cherries escape through the opening 9 on to the sector 3, if they have long stems, the stems will catch against the lower edge 110 of the plate *I* substantially as illustrated in Fig. 1, and the cherry will find lodgment substantially in the position shown in full lines on the said sorter. Where the cherry has a short or broken stem, it will ultimately 115 occupy the dotted position illustrated in Fig. 1 on the sorter 3.

The width of the grooves 4 is sufficiently greater than the diameter of a cherry so as to permit the cherries without stems to race 120 therethrough into the receptacle 10. By confining the path of movement of said cherries through the grooves 4, it will be clear that there will be no possibility of the cherries with stems, or portion of stems, 125 having sufficient lateral movement to prevent the stems from causing them to lodge on said sorter. I have found that this machine enables me to sort broken cherries from whole cherries. The broken fruit 130

which is of course much more irregular in form than a whole cherry, will find lodgment on the sorter 3 and will ultimately be deposited in the receptacle 11.

While I have described my machine as designed to be used in connection with my machine for stemming cherries already mentioned, still I do not confine myself to using my present machine in connection with the said machine, nor in fact in connection with any particular type of cherry stemming machine, nor in connection with any cherry stemming machine. This machine in question of course may be used for sorting various kinds of small fruit other than cherries. The bottom of each pocket D is pierced by a hole 1 which preferably opens into the interior of the cylinder B, which is cored out in places for the sake of lightness in construction. These holes are placed preferably centrally of the pockets D, and being of lesser diameter than the said pockets form annular shoulders m against which the fruit rests. The provision of the said holes permits small particles to pass through the pockets D and so prevent them from clogging up. These holes 1 also prevent any danger of the fruit being held within the pockets D by air suction 30 when these pockets reach their lowermost position.

While I have described what I consider to be the best embodiment of my invention, I desire it to be understood that the principles can be embodied in different forms and I desire not to be limited beyond the requirements of the prior art, and the terms of my claims.

What I claim as my invention is:

1. In a machine of the class described, the combination with a sorter provided with a plurality of grooves the bottoms or floors of which normally occupy an angular position to the horizontal, and journaled in the machine frame; said machine frame, means for periodically rotating said sorter, and means for distributing fruit into the grooves of said sorter at their upper ends.

2. In a machine of the class described, the combination with a sorter provided with a plurality of transverse parallel grooves the bottoms or floors of which normally occupy an angular position to the horizontal, and journaled in the machine frame; said machine frame, means for periodically rotating said sorter, and means for distributing fruit into the grooves of said sorter at their upper ends.

3. A machine for sorting fruit comprising a machine frame, a rotary cylinder journaled in said frame and longitudinally provided in its outer surface with a plurality of alined pockets; means whereby fruit is introduced into said pockets; a sorter journaled in said machine frame be-

low said cylinder and provided with a plurality of grooves in alinement with the said pockets, the floors or bottoms of said grooves normally occupying an angular position to the horizontal; means for periodically rotating said sorter, and a plurality of guiding chutes positioned between said cylinder and said sorter whereby the fruit dropping from said pockets is conducted to said grooves, as set forth. 70

4. A machine for sorting fruit comprising a machine frame; a rotary cylinder journaled in said frame and longitudinally provided in its outer surface with a plurality of alined pockets, a portion of said cylinder 80 in advance of the said pockets being removed to remove entirely the greater portion of one side of each of the said pockets, thereby forming a ledge or shelf which moves in advance of said pockets to facilitate the passage of fruit thereinto, a hopper containing the fruit positioned adjacent said cylinder; a sorter journaled in said machine frame below said cylinder and provided with a plurality of grooves in alinement with the 90 said pockets, the floors or bottoms of said grooves normally occupying an angular position to the horizontal; means for periodically rotating said sorter, and means for feeding fruit one at a time to the sorting 95 mechanism, as set forth.

5. A machine for sorting fruit comprising a machine frame; a rotary cylinder journaled in said frame and longitudinally provided in its outer surface with a plurality 100 of alined pockets, a portion of said cylinder in advance of the said pockets being removed to remove entirely the greater portion of one side of each of the said pockets, thereby forming a ledge or shelf which moves in 105 advance of said pockets to facilitate the passage of fruit thereinto; a hopper containing the fruit positioned adjacent said cylinder; a sorter journaled in said machine frame below said cylinder and provided with a 110 plurality of grooves in alinement with the said pockets, the floors or bottoms of said grooves normally occupying an angular position to the horizontal; means for periodically rotating said sorter, means for feeding 115 fruit one at a time to the sorting mechanism, and a shield positioned in proximity to said cylinder to prevent the fruit from prematurely escaping from said pockets therein, as set forth. 120

6. In a machine of the class described, the combination with a sorter provided in each side with a plurality of alined transversely extending grooves, the bottoms or floors of which normally occupy an angular position 125 to the horizontal, and journaled in the machine frame; said machine frame, and means for periodically rotating said sorter and locking it in normal position, of a plurality of guiding chutes positioned above the up- 130

per side of said sorter, and comprising front and back plates and a plurality of partitions spaced apart forming said chutes which are in alinement with said grooves; the lower 5 edge of said front plate positioned some distance above the lower ends of said partitions to form a discharge opening at the lower end of each of the said guiding chutes; means for supporting said plates, and means 10 for feeding fruit to said sorter through said guiding chutes.

7. A cylinder for the purpose specified, provided in its outer surface with a plurality of alined pockets, a portion of said cylinder

in advance of said pockets being removed 15 so as to remove entirely the greater portion of one side of each of the said pockets, thereby forming a ledge or shelf which extends between the outer sides of the pockets at each end of the cylinder in a continuous 20 and unbroken form to facilitate the passage of fruit into said pockets, as set forth.

In testimony whereof I have affixed my signature in presence of two witnesses.

FRANK ROBBINS SMITH.
